UNITED STATES PATENT OFFICE.

MARK T. STANTON, OF CLEVELAND HEIGHTS, OHIO, ASSIGNOR TO THE ELECTRIC RAILWAY IMPROVEMENT COMPANY, OF CLEVELAND, OHIO, A CORPORATION OF OHIO.

RAIL-BOND PROTECTOR.

1,390,468.

Specification of Letters Patent. Patented Sept. 13, 1921.

Application filed May 31, 1917. Serial No. 171,972.

To all whom it may concern:

Be it known that I, MARK T. STANTON, a citizen of the United States, and a resident of Cleveland Heights, county of Cuyahoga, 5 and State of Ohio, have invented a new and useful Improvement in Rail-Bond Protectors, of which the following is a specification, the principle of the invention being herein explained and the best mode in which 10 I have contemplated applying that principle, so as to distinguish it from other inventions.

The present invention, relating as indicated to rail bond protectors, is particularly 15 adapted to bonds attached to the heads of rails, and having the body of the bond extending alongside of the usual fish plate which is used to connect the two rails together. The present device is intended to 20 constitute a secure and extremely simple protecting covering for such a bond, which will permit inspection of the bond terminals, at any time, but which will prevent the mutilation or removal of the bond from the rails. 25 To the accomplishment of the foregoing and related ends, said invention, then, consists of the means hereinafter fully described and particularly pointed out in the claims.

The annexed drawing and the following 30 description set forth in detail certain mechanism embodying the invention, such disclosed means constituting, however, but one of various mechanical forms in which the principle of the invention may be used.

35 In said annexed drawing:—

Figure 1 is a side elevation showing a bond protected by my improved device; Fig. 2 is a section on the line 2—2, Fig. 1; Fig. 3 is a side elevation similar to Fig. 1, but 40 showing a modified type of protector; and Fig. 4 is a section on the line 4—4, Fig. 3.

In Fig. 1 there is shown a rail bond 1 of U-shape, having its terminals 1 integrally united to the adjacent ends of rails 2, the 45 bonds being applied to the side of the head of the rail, and the U-shaped body portion of the bond extending along-side of a fish-plate 3 attached to the two rails. It will be understood that the particular bond shown 50 in the drawings is merely illustrative of a number of types which may be used, and my improved device will require but little modification to conform to these different shapes.

In order to protect the bond from muti-

lation or from removal from the rail by 55 being cut through below the two terminals, I provide a protecting plate or cover 4 of substantially rectangular shape which is provided with two upwardly extending arms 5 of substantially the same width as the 60 width of the bond at that point, these arms 5 lying closely against the sides of the bonds, and extending slightly above the juncture of the body portion of the bond with the terminals. Between the arms 5 there is provided an extending tongue 6 which is bent 65 inwardly into contact with the fishplate 3, and which may be integrally attached to the fishplate if desired. Each of the arms 5 is also provided with a laterally extending lug 70 7 which is bent around the side of the bond into contact with the fishplate.

The protecting plate 4 is preferably attached to the fishplate by being welded at the lugs 7, as well as at the top of the tongue 75 6, and along the bottom of the plate proper. When so fastened to the fishplate it is impossible for anyone to get at the body of the bond to sever the same from the terminals or to mutilate the same in any way, while 80 the removal of the plate 4 is an extremely difficult matter if the latter is integrally joined to the fishplate, which can be readily accomplished by welding.

In Figs. 3 and 4 a modified type of protecting plate is shown, in which the body portion of the plate is provided with upwardly extending arms 10 formed to substantially cover the bond terminals 1 and provided at either end with a downwardly bent lug 11 90 adapted to contact and to be welded to the upper edge of the fishplate. This modified type of plate is provided as in the first form with a central forwardly extending tongue 12, which is welded to the fishplate, as is the 95 bottom of the cover proper.

The chief differences between the two forms of protecting plates shown in Figs. 1 and 3 is in the covering of the bond terminals by the plate of the latter figure, and 100 while this is not always necessary, it is desirable in connection with certain types of bonds, and under certain circumstances my improved protector forms, in connection with the fishplate, substantially an inclosing casing for the bond which so covers the same that even though the bond were not attached to the rail it could not be with- 105

drawn, while to secure access to the bond to remove it is impossible unless the plate is first removed.

Other modes of applying the principle 5 of my invention may be employed instead of the one explained, change being made as regards the mechanism herein disclosed, provided the means stated by any of the following claims or the equivalent of such 10 stated means be employed.

I therefore particularly point out and distinctly claim as my invention:—

1. The combination with two abutting rail ends, a fishplate connecting the same 15 and a bond having its terminals attached to the heads of said rails, and its body portion extending downwardly therefrom in U-shape adjacent to said fishplate, of a protecting plate disposed adjacent to such U- 20 shaped bond body, and extensions on said plate disposed above and below such bond body and integrally connected to said fishplate.

2. The combination with two abutting rail ends, a fishplate connecting the same 25 and a bond having its terminals attached to the heads of said rails, and its body portion extending downwardly therefrom in U-shape adjacent to said fishplate, of a protector plate of the same metal as said fishplate and disposed adjacent to such U- 30 shaped bond body, said plate being integrally joined to said fishplate above and below and on either side of the U-shaped body portion of said bond.

3. The combination with two abutting rail

ends, a fishplate connecting the same and a bond having its terminals attached to the heads of said rails, and its body portion extending downwardly therefrom in U-shape 40 adjacent to said fishplate, of a roughly U-shaped protector plate formed to cover the body portion of said bond when disposed adjacent thereto and provided with extensions integrally joined to said fishplate 45 above and below and on either side of the body portion of said bond.

4. The combination with two abutting rail ends, a fishplate connecting the same and a bond having its terminals attached to 50 the heads of said rails, and its body portion extending downwardly therefrom in U-shape adjacent to said fishplate, of a roughly U-shaped protector plate formed to cover the entire exposed side of said bond when 55 disposed adjacent thereto, said plate being formed with extensions partially inclosing the terminal portions of said bond and being integrally joined to said fishplate above and below the body portion of said bond and 60 also at either side thereof.

5. In a combination with two abutting rail ends a fishplate connecting the same, and a bond having its terminals attached to said rails, of means positioned to substantially 65 inclose the portion of said bond between its terminals, said means being homogeneously united to said fishplates both above and below the body portion of said bond.

Signed by me, this 18th day of May, 1917.
MARK T. STANTON.
